INVENTOR

UNITED STATES PATENT OFFICE.

JAMES W. IVORY, OF PHILADELPHIA, PENNSYLVANIA.

INTERCHANGEABLE ARTIFICIAL TOOTH.

1,081,307.

Specification of Letters Patent.

Patented Dec. 16, 1913.

Application filed October 26, 1912. Serial No. 727,834.

To all whom it may concern:

Be it known that I, JAMES W. IVORY, a subject of the King of Great Britain, residing in the city and county of Philadelphia, State of Pennsylvania, have invented a new and useful Interchangeable Artificial Tooth, of which the following is a specification.

My invention relates to anchors of that class attachable to an artificial tooth or crown, and a facing plate attachable to said anchor adapting said plate for interchangeable teeth and providing a firm and reliable connection for said plate with said anchor, and consequently with a bridge or other work, as will be hereinafter set forth.

The invention is satisfactorily illustrated in the accompanying drawing, but the important instrumentalities thereof may be varied, and so it is to be understood that the invention is not limited to the specific arrangement and organization shown and described.

Figure 1 represents a perspective view of an artificial tooth with an anchor thereon embodying my invention. Fig. 2 represents a perspective view of the facing plate employed. Fig. 3 represents a perspective view of another embodiment of my invention. Fig. 4 represents a horizontal section thereof on line $x-x$, Fig. 3. Fig. 5 represents a perspective view of the tooth having the facing plate partially applied thereto. Figs. 6, 8 and 10 represent rear elevations of a tooth as other embodiments of my invention. Fig. 7 represents a horizontal section on line $y-y$ Fig. 6. Fig. 9 represents a horizontal section on line $z-z$ Fig. 8. Fig. 11 represents a horizontal section on line $a-a$ Fig. 10. Fig. 12 represents an elevation of another embodiment of the facing plate. Fig. 13 represents a horizontal section thereof on line $b-b$ Fig. 12. Fig. 14 represents an elevation of another embodiment of the invention. Fig. 15 represents a vertical section on line $c-c$ Fig. 14. Fig. 16 represents a horizontal section on line $d-d$ Fig. 14. Fig. 17 represents a section of another embodiment.

Similar numerals of reference indicate corresponding parts in the figures.

Referring to the drawings, 1 designates an artificial tooth or crown which excepting the feature of my invention applied thereto is of usual order. On the sides of the tooth are the recesses 2 which are adapted

for the attachment to said tooth or crown of a backing for the same, said backing consisting of a plate 3 of metal which with the tooth or crown has interengageable appendages for connection with each other, as will be hereinafter described. Attached directly to the tooth is an anchor or anchor plate 13 see Fig. 1, which consists of a piece of metal bent on itself forming the outwarded lips 4 and inward deflections forming the limbs 5 which are embedded in the tooth or crown and thus retained firmly therein. The anchor plate is made of platinum which will endure the high heat to which it will be subjected in the porcelain furnace.

To the plate 3 are secured in any suitable manner see Fig. 2, the longitudinally extending lips 6 which are inturned, and adapted to be presented to the lips 4 as shown in Fig. 5 and by longitudinal movements of either tooth or plate, causing the engagement of the plate with the tooth in a firm and reliable manner, while the lingual side of the tooth is completely covered by said plate forming a smooth plain surface so as to prevent the possibility of solder or other substance reaching the porcelain or material of the tooth or crown, while the operator is forming a bridge and obtain a free action in the connection of the tooth with a bridge or other work.

It will be noticed that the recesses 2 are set in from the lateral terminals of the lips 4 so as to provide spaces for the inturned lips 6 of the backing plate 3, and thus cause said plate to lie flat on the back of the tooth and consequently even therewith.

In Fig. 3, I show the ends of lips of members 6 separate from each other in the longitudinal direction of the plate, said ends being secured to the plate by riveting, heading or other suitable means, see Fig. 4.

In Figs. 6 and 7, the anchor plate is fastened to the tooth or crown by the pins 7 which are placed in horizontal direction and passed through said anchor plate into the tooth or crown.

In Figs. 8 and 9, the anchor plate 13 is fastened to the tooth or crown by the pins 8 which are placed in vertical position and passed through said anchor plate into the tooth or crown.

In Figs. 10 and 11, the anchor plate is constructed of a piece of metal bent on itself to form the narrow outturned lips 4, and

the limbs 5, both of somewhat dovetailed form.

In Figs. 12 and 13, the inturned lips 6 are formed on a plate 9 which is attached to the backing 3 by the pins 10, said plate being set in a depression in said backing, said depression being clearly seen in Fig. 13.

In Figs. 14, 15 and 16, the anchor plate 13 has inturned lips 11 which embrace the side edges of the tooth or crown 1 and is otherwise secured to the tooth as at 12, and so retains tight connection with the latter, and the recesses 2 are on said side edges adjacent to said lips so as to secure the inturned lips 15 of the backing plate to be applied thereto. In said Figs. 14, 15 and 16 the anchor plate as in all other cases is embedded the thickness of its metal into the body of the tooth, the limbs on the edges of said plate also penetrating said body. This with the pins employed make a strong and reliable attachment for said plate with the material.

Fig. 17 shows an anchor which is composed of a plate 13 folded on itself to form the side lips 4 and the legs 5 which are spread apart and embedded in the tooth and baked therein forming a strong connection for the anchor. In this figure the tooth is provided with recesses 2 for the lips of the backing plate as in the previous instances. The pins 7 and 8 may be formed of platinum as has been stated of the anchor plate, but if desired, the latter may be made of less expensive metal and secured to the tooth by 35 platinum attachments in the latter, said plate being brazed to said attachments.

The operation is as follows: The backing plate is soldered to a bridge or other denture, and reinforced on the back thereof. The tooth is then applied to said plate and the lips 6 of the latter engaged with the lips 4 of the anchor and fitted in position and cemented, the gold on the biting edge of the tooth being burnished. In the event of fracture, a tooth may be removed, and another tooth substituted therefor, fitted and secured without destroying or affecting the other parts of the bridge or denture as adjusted to the mouth. In case of a crown, a pin is soldered to the upturned part of the backing plate, as shown in dotted lines, whereby the dentist is enabled to use this style of an attachment in adjusting the same.

Attention is directed to the fact that the anchor plate in the main is embedded in the tooth the thickness of its metal, and thus said plate is on an even plane with this surface of the porcelain of the tooth, where-

by as the lips of the back plate engage the lips of the anchor plate, the backing plate will slide evenly over the anchor plate and the uncovered portions of the lingual face of the tooth, while the backing plate as constructed, will prevent solder from reaching the tooth or obstructing the free union of the anchor plate therewith.

Having thus described my invention what I claim as new and desire to secure by Letters Patent, is:—

1. In an artificial tooth, an anchor plate 70 having free edges forming lips engaging and overhanging recesses in the body of the tooth, and means extending in opposite directions from a backing to engage the free edges of the anchor plate.

2. In an artificial tooth, a backing plate adapted for the lingual side of the tooth, and an embedded anchor plate on the tooth flush therewith and projecting upon opposite sides, said anchor and backing plates 80 being provided with engaging means for firm connection thereof and admitting of said plates being seated even with the surface of the tooth.

3. An artificial tooth having an embedded 85 anchor plate flush thereon with portions projecting upon opposite sides, and a removable backing plate for the lingual side of the tooth, said backing plate and anchor plate having engaging members and the tooth provided with recesses for the engaging members of said backing plate, and the free edges 90 of said anchor plate therein.

4. In an artificial tooth, a backing plate 95 for the lingual side thereof, said plate having inturned lips thereon, and an anchor plate fixed on said tooth, said anchor plate having outturned lips extending in opposite directions, said lips of the anchor and backing plates being engageable, and said tooth having recesses therein adapted for the reception of the lips of the backing plate and the projection of the free edges of the anchor plate.

5. An artificial tooth having recesses on 105 the side thereof, a backing and an anchoring plate having outturned lips and inward deflections embedded in the recesses of the tooth, said recesses being set in from the lateral terminals of said lips and providing 110 space for the inturned lips of the backing plate.

J. W. IVORY.
